UNITED STATES PATENT OFFICE

ADAM A. SANDERS, OF NEW YORK, N. Y.

BACK WASHER

Application filed January 17, 1928. Serial No. 247,393.

This invention relates to a convertible article designed to enable a person to effectively scrub and wash the back and other parts of the body, and to be used as a medical bandage.

5 One of the objects of the invention is the provision of an article of the indicated character which embodies means adapted to contain a detergent or liquid soap or soapy solution which will reach the parts of the body 10 being scrubbed and washed in the manipulation of the article.

Another object of the invention is the provision of an article of the indicated character which may be readily converted from a 15 back washer to an article adapted to be placed upon one hand to be used for scrubbing and washing other parts of the body than the back.

Another object is to provide an article of 20 the indicated character which embodies novel features of construction whereby the article may be readily converted to be used as a medical appliance for bandaging parts of the body and for holding poultices in place 25 on affected or injured parts of the body.

With the foregoing and other objects in view the invention resides in the certain structural features and functions of the parts hereinafter fully described and illustrated in the 30 accompanying drawing, in which:

Figure 1 is a rear elevation of the article embodying the features of the invention with portions of the manipulating strip being broken away, in condition to be used as a 35 back scrubber and washer.

Fig. 2 is a front elevation of the article.

Fig. 3 is a rear elevation of the article converted to be used with one hand.

Fig. 4 is a sectional view taken on the line 40 4—4, Fig. 3.

Fig. 5 is a sectional view taken on the line 5—5, Fig. 2.

Fig. 6 is a perspective view of the neck of the pouch of the article with its closure 45 opened.

Fig. 7 is a perspective view of the neck of the pouch illustrating the neck opened.

Fig. 8 is a sectional view illustrating a modification.

50 The form of the invention shown in the

drawing is by way of example only, and it is therefore to be understood that modifications in the construction and arrangement of the parts and in the character of the materials used may be adopted without departing from 55 the spirit of the invention.

In the illustrated embodiment of the invention, use is made of a piece of textile material to produce a backing strip 10, the said material being cut, sewed and formed to provide 60 a comparatively large central portion 11, and comparatively narrow elongated grip or manipulating members 12 respectively at opposite ends of the central portion. The backing strip 10 may be of any preferred size, 65 and the central portion and the members 12 may be of any preferred proportions. In order to stiffen the central portion 11 there are provided a plurality of stiffening members 13 of suitable material such as whalebone, and these stiffening members 13 are disposed crosswise of the central portion at one side and are held in place in spaced relationship in any suitable manner. In the present instance a piece of textile material 14 70 is used, the same being somewhat shorter than the central portion 11 but equal in width. The piece of material 14 is sewed to the central portion along the marginal edges thereof, and lines of stitching along the opposite 75 side edges of the stiffening members 13 hold them in place.

A suitable bag, sack or pouch 15 of rubber or like material is attached to the central portion 11, and occupies a position at one side 80 of the longitudinal axis of the strip 10. The pouch 15 serves for containing a detergent or soapy solution which will reach the parts of the body being scrubbed and washed through small perforations or pinholes 16 in the wall of the pouch. The detergent or soapy solution is introduced into the pouch 15 through a neck 17. At the mouth of the neck 17 there are provided flexible members 18, there being one at each side and secured to the neck in any suitable manner. The flexible members 18 normally serve to hold the neck closed, 85 supplemented by the action of a retaining element or clip 19 pivotally connected at one end as at 20 to the members 18. When the 100

clip 19 is moved to the opened position as shown in Fig. 6, the flexible members 18 may be bowed by exerting pressure with the fingers of the hand on the opposite ends thereof 5 to open the neck, as shown in Fig. 7. Use is made of a scrubbing or washing element, such as a ruffled or pleated cloth 21 which is secured to the central portion 11 of the backing strip 10 adjacent the pouch 15. It will now 10 be apparent that the article having the features hereinabove described may be used by a person for effectively scrubbing and washing the back. The article may be manipulated by gripping the ends of the members 12 15 with the pouch 15 and cloth 21 in contact with the skin. In the manipulation the detergent or soapy solution will be forced out of the pinholes 16 by pressure and will reach the parts of the body while the cloth 21 will set 20 up the desired scrubbing and washing action.

In order that the article may be readily converted from a back washer to an article adapted to be placed upon one hand to be used for scrubbing and washing other parts of the 25 body than the back, there is provided a tab 22 which is sewed at one end to the central portion 11 at the rear thereof. The tab 22 extends through a loop 23 secured to the portion 11. A second and smaller tab 24 is 30 secured to the tab 22 and has coacting fastening elements 25 and 26 respectively at the opposite ends thereof. The central portion 11 has a fastening element 27, one of the members 12 has a duplex fastening element 35 28, and the other member 12 has a fastening element 29. The arrangement of the fastening elements 27, 28 and 29 is such that the fastening element 28 may be engaged with the fastening element 27 after folding the manipulating member 12 over the central portion 11, and the fastening element 29 may be engaged with the duplex fastening element 28 after the related manipulating member 12 has been folded over the central portion 11 40 and then folded upon itself. The tabs 22 and 24 may be folded upon themselves around the folded manipulating members 12, and then by bringing the fastening element 26 into engagement with the fastening element 45 25, the manipulating members 12 will be retained in place in folded condition, as shown in Figs. 3 and 4. Suitable means in the form of an elastic strip or band 30 secured to the portion 11 at the rear serves for holding the 50 neck 17 down at the rear of the portion 11, as shown in Fig. 3. The portion 11 also has a strip or band 31 at the rear. When the article is used in the condition shown in Fig. 3 one hand may be inserted under the band 31 55 while two or more of the fingers may be inserted in the loop formed by the tabs 22 and 24 with the thumb and little finger free to manipulate portions in conjunction with the hand for carrying out scrubbing and washing 60 operations. Rings 32 attached to the portion 65

11 at the rear serve for hanging up the article when not in use.

Instead of permanently securing the pouch 15 and the scrubbing and washing element 21 to the central portion 11, these parts may be 70 permanently attached to a piece of rubber or like material 33 which has secured on one face thereof fastening elements 34 which coact with fastening elements 35 on the central portion 11 to detachably connect the unit consisting of the pouch 15 and the element 21, 75 as shown in Fig. 8.

I claim:

1. The combination of a scrubber, and a pouch of flexible waterproof material secured to said scrubber, said pouch having a neck by which the pouch is filled with any desired liquid, a wall of said pouch having perforations through which the liquid may be discharged, relatively stiff but flexible members secured to opposite sides of the neck and having a normal tendency to collapse the neck, and a movable clip adapted to embrace the neck to hold it closed. 80

2. The combination with a strip of textile material having grip members at the opposite ends thereof for manipulating said strip, and a central ruffled section, of a pouch adapted to contain and discharge liquid soap or the like, said pouch being secured to said strip adjacent said ruffled section. 90
